UNITED STATES PATENT OFFICE.

HENRY STUTSMAN, OF EAST PORTLAND, OREGON.

STEAM-GENERATOR.

SPECIFICATION forming part of Letters Patent No. 328,531, dated October 20, 1885.

Application filed January 23, 1885. Serial No. 153,750. (No model.)

To all whom it may concern:

Be it known that I, HENRY STUTSMAN, of East Portland, in the county of Multnomah and State of Oregon, have invented an Improved Steam-Generator with Improved Circulating-Tubes, of which the following is a specification.

My improvement consists of a water-base and a vertical column of cylinder form provided with my improved circulating-tubes.

The objects of my improvements are to provide a vertical column with a water-base, the circulating coil-tube fire-grate, and circulating-tubes for the purpose of rapidly generating steam. I attain these objects by the mechanism illustrated in the accompanying drawings, in which—

Figure 1 is a detached half-sectional view of my improved circulating-tube as it appears with the circulating-plate removed; Fig. 2, a detached and half-sectional view of the tube and circulating-plate; Fig. 3, a detached view of said plate, representing the top or bottom sides; Fig. 4, a detached and edge view of the circulating-plate; Fig. 5, a top view of the circulating coil of pipe; Fig. 6, a vertical section of the entire generator; Fig. 7, a horizontal sectional view as it appears with the bonnet removed.

Similar letters refer to similar parts throughout the several views.

The vertical column c' is riveted and secured to the water-base B , and which column extends upward and partly incased in the smoke-stack, as shown in Fig. 6, and which part serves as the steam-drum D , and the middle portion of which is provided with the circulating-tubes a^2 , and with the lower base, B , and the coil c serve as the water-space. The tubes a^2 , as shown in Figs. 2 and 6, are provided with the separate circulating-plates a' . Said plates are provided with the lugs $a a$,

which prevent the plates from passing through the tube a^2 any farther than flush with the inner end, as shown in Figs. 2 and 6, and which is inserted into the tube from the outer end before the end cap is screwed on, by which means the lugs $a a$ are retained between the end of the tube and said cap. Said plates a' cause the water to flow outward from the column c' in the lower half of the tubes a^2 , and return to the said column through the upper half of said tube, as indicated by the arrows as shown in Figs. 2 and 6. The coiled tube c is connected with the water-base B and the column c' , which serves as a circulating tube from the base to the column, and also as a fire-grate. The outer casing, c^2 , slips down over the water-base B and rests on the rivets of said base, as shown in Fig. 6. The upper end of the casing c^2 is provided with the bonnet a^2 , which is secured on the upper end of the casing c^2 , as represented in Fig. 6. The casing or outer wall, c^2 , is also provided with two doors, $D D$, communicating with the fire-box f for the reception of fuel, and also two damper-doors, $D^2 D^2$. It will be further observed that the generator is provided with a safety-valve and the escape-pipe P ; also the water-glass, as shown in Fig. 6.

Having thus described my invention, I claim as new, and desire to secure by Letters Patent—

1. In a steam-generator constructed as described, the water-base B , in combination with the vertical column c' , the fire-grate coil c , as described and set forth.

2. In a steam-generator constructed as described, the plate a' , with the lugs $a a$, in combination with the tube a^2 , as and for the purpose set forth.

HENRY STUTSMAN.
